(57) **CLAIM**

What is claimed is an ornamental design for a charger for electronic devices, as shown and described.

DESCRIPTION

FIG. 1 is a front, top, and left side perspective view of a charger for electronic devices showing our new design;

FIG. 2 is a front, bottom and right side perspective view thereof, rotated 180 degrees;

FIG. 3 is a top plan view thereof;

FIG. 4 is a bottom plan view thereof;

FIG. 5 is a right side elevational view thereof;

FIG. 6 is a left side elevational view thereof;

FIG. 7 is a front elevational view thereof;

FIG. 8 is a rear elevational view thereof, rotated 180 degrees;

FIG. 9 is a top, front, left side perspective view of the charger for electronic devices of FIG. 1, shown in a first condition of use;

FIG. 10 is a top, front, left side perspective view of the charger for electronic devices of FIG. 1, shown in a second condition of use; and,

FIG. 11 is a top, front, left side perspective view of the charger for electronic devices of FIG. 1, shown in a third condition of use; and,

FIG. 12 is a top, front, left side perspective view of charger for electronic devices of FIG. 1, shown in a fourth condition of use.

The broken lines depict portions of the charger for electronic devices that form no part of the claimed design.
